UNITED STATES PATENT OFFICE

2,457,499

FIRE ALARM TRIP MECHANISM

Joseph Philip Santole, Waterbury, Conn.

Application May 9, 1945, Serial No. 592,767

2 Claims. (Cl. 74—2)

1

This invention relates to fire alarms and has for an object to provide an extremely simple and inexpensive means for signaling a fire.

Another object of my invention is to provide a very cheap device whereby a mechanical, or electrical, alarm means may be actuated.

A further object of the invention is to provide in an alarm actuating device an easily fusible member for holding the alarm out of action.

Other features and advantages will become more readily apparent from the following description and the accompanying illustrative drawings in which:

Figure 1 is a front elevational view of my fire alarm device,

Figure 2 is a side elevational view thereof,

Figure 3 is a top plan view,

Figure 4 is a perspective view of a broken away part of the device, certain elements being shown in changed position, and

Figure 5 is a view similar to Figure 2, illustrating a modification and certain parts being broken away.

In the accompanying drawings as above enumerated and in the following specification, like characters of reference indicate like parts throughout and in which 10, indicates my invention which consists of a bracket 11, as shown, stamped from sheet metal; however, it may just as well be formed of wire. The top wall 12, of member 11, is turned outwardly at right angles and is provided with an extension tongue 13, having a detent 14, therein upon which is hung a Lipowitz or other easily fusible member 15. To the lower end of this member is attached through the eye 16, a hook end 17, of a rod 18, which passes slidably through aligning openings 19 and 20, in the offsets 21 and 22, of the member 11. Between the member 22, and a contact member 23, fixedly secured to the lower end 24, of member 18, is seated a coil spring 25, of a rather weak nature, which spring is adapted to normally force the member 18, down. An opening 26, is provided adjacent the upper end 27, of the member 11, whereby the bracket may be suspended upon a hook or nail.

The contact member 23, is also adapted for use as a lever for bearing down upon an alarm release arm (not shown) or the member 23, may contact and close an electric circuit (not shown).

In Figure 5, I show a modification of the invention in which a coil spring 28, is suspended from the bracket arm 29, of the member 11'. To the lower end of spring 28, is suspended a fusible member 30, upon the arm 31, of which is suspended a release member 32, which as in the former instance may release an alarm clock control or close an electric circuit.

2

The operation of the device is obvious, as over-heating of any room or place where the device is standing will melt the member 15, resulting in giving an alarm of fire.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

1. An alarm device comprising a support including an upper arm, an extension integral with

20 said support, apertures in said extension and a fusible link having an eye at one end attached to said arm, an eye on the opposite end of said link, an alarm control link, a tongue at one end and a contact at the other end thereof, said

25 tongue being received in said second mentioned eye and said control link being slidably received in said apertures, a spring encircling said control link engaging said extension and said contact and tensioning said control link.

30 2. An alarm device comprising a support having an integral extension and aligned apertures in said extension and an arm, a detent in said arm, a fusible link having eyes at the terminal portions thereof, one of said eyes positioned in

35 said detent, a control link having a hook slidably received in said apertures and attached to the other of said eyes, a contact secured to the shank of said link, a spring positioned around said link, engaging said extension and said contact, tensioning said control link.

40 JOSEPH PHILIP SANTOLE.
